UNITED STATES PATENT OFFICE.

ROBERT E. HODGMAN, OF DENVER, COLORADO, ASSIGNOR TO THE BABESPUNE COMPANY, OF DENVER, COLORADO, A CORPORATION OF COLORADO.

BABY MEDICINE SPOON.

Application filed November 23, 1926. Serial No. 150,231.

This invention relates to improvements in spoons and has particular reference to spoons of the type used for feeding small children and for giving them medicine.

5 It is well known that it is very difficult to administer medicines, such as castor oil, to a child with an ordinary spoon as the child will instinctively close its mouth and lips making it impossible to transfer the 10 medicine from the spoon to the child's mouth. It is, therefore, often necessary to forcibly open the child's mouth and to pour the medicine therein. This sometimes produces a strangling and is altogether unsatisfactory.

15 It is the object of this invention to produce a spoon which is constructed in such a manner that the child's lips cannot come into contact with the contents and which permits the contents to flow freely into the child's 20 mouth once the spoon has been inserted.

My invention, briefly described, consists of a spoon made in two parts, one of which serves as a cover for the front end of the lower or spoon part, and which has a cut out 25 portion or notch at its front end through which the liquid can flow. The cover portion provides a cap for the baby to bite on and prevents it from getting its lips into contact with the contents of the spoon. The cover 30 also prevents the medicine from being spilled so that the child gets the full dose prescribed by the doctor.

The construction is such that the spoon is also adapted to serve as a teething device 35 having a smooth attractive surface that is cooling to the gums, which are usually feverish during dentation.

It is a further object of this invention to so construct the spoon that it may be readily 40 cleaned and kept in a sanitary condition and which will stand upright upon a flat surface.

The above and other objects that may become apparent as the description of the invention proceeds are attained by means of a 45 construction that I will now describe in detail, reference for this purpose being had to the accompanying drawing in which the preferred form of the invention has been illustrated and in which:

- 50 Fig. 1 is a top plan view of the spoon;
Fig. 2 is a side elevation thereof;
Fig. 3 is a top plan view showing the cover disconnected from the spoon;
Fig. 4 is a section taken on line 4—4, Fig. 52; and

Fig. 5 is a perspective view showing the parts in operative position.

My improved spoon comprises two parts which have been designated respectively A and B. The part A is the spoon portion and 60 consists of a spoon of ordinary shape and size, provided at one end with a handle 5 which is bent into a closed loop, the end 6 of the handle terminates adjacent to the bottom of the spoon near the rear end there- 65 of and is preferably soldered to the spoon at this point. The shape of the spoon portion is shown quite clearly in Figure 3 and when considered apart from the cover portion is very much like ordinary baby spoons 70 with curved handles. Secured to this spoon portion is the cover portion B which has a part of substantially the same contour as the spoon and this part is provided with in- turned flanges 7 (Fig. 4) which are adapted 75 to engage the outer portion of the spoon in the manner indicated so as to firmly attach the two parts. The point of the cover portion is provided with a notch or cut out 8 (Fig. 1) which forms an opening that com- 80 municates with the space enclosed thereby. The cover portion has a rearwardly extending loop 9 that is interlinked with the handle so as to prevent the cover from being sepa- 85 rated from the spoon. The lower portion of the handle which has been indicated by reference numeral 10 has an upwardly extending integral tongue 11 that is adapted to be engaged by the rear end of the loop 9 so as to hold the cover in position on the spoon, 90 all as shown in Figures 1, 2 and 5. When the parts are in this position any liquid such as medicine, fruit juices or any other liquid that is desired to give or administer to the child, is placed in the spoon portion in the 95 ordinary manner. The spoon is then inserted into the mouth of the child and by properly inclining the same, the liquid flows out through the notch 8. The cover portion B forms a cap which prevents the child's lips or its gums or teeth from entering the liquid in the spoon and in this manner makes it im- 100 possible for the child to prevent the adminis- tration of the medicines. The cover also serves to prevent the contents of the spoon from being spilled due to unsteady handling as is often the case when an uncovered spoon of ordinary construction is employed. The spoon, although especially valuable for ad- 105 ministering medicines, can, as above inti- 110

ated, be used for any other purpose, such as the eating of liquid foods or fruit juices or when in open position like that shown in Figure 3, which can be used for any purpose for which a similar uncovered spoon may be employed. The fact that the two parts A and B can be moved to the position shown in Figure 3, makes it possible to clean the spoon so as to always have it in a perfectly sanitary condition. This would be very difficult if the cover portion B were made integral with or otherwise nonremovably secured to the spoon. Although I have shown an attaching lug 11 which is stamped from the material of the handle in the manner indicated in Figures 2 and 5, it is evident that this might be replaced by any equivalent means, such, for example, as a rivet projecting inwardly from the handle.

It will be noted from Figure 3 that the lower portion of the looped handle, which portion has been indicated by numeral 10, is quite wide and flat and therefore serves to hold the spoon in upright position when it is placed on a flat supporting surface. This is very desirable for the reason that the spoon, even when it is filled with a liquid, can safely be set down upon a table without danger of spilling the contents. The parts are so proportioned that the upper edge of the spoon is substantially parallel with the plain surface upon which the spoon rests and as it is usually rested on a horizontal surface, it is evident that the liquid will not flow out, even though the spoon is filled substantially to the brim. The spoon, when in assembled position like that shown in Figures 1, 2 and 5, is admirably adapted

for a teething device as it presents two curved smooth surfaces, which are conveniently arranged for the child to bite on and which have a cooling effect on the gums.

The spoon also serves as an interesting plaything as it can be readily disconnected into the position shown in Figure 3 in which position the child finds considerable amusement in attempting to readjust the parts and otherwise altering their relative positions.

From the above it will be noticed that I have produced a spoon of a novel construction that is admirably adapted for several different purposes and is especially useful in the administering of medicines to children.

Having now described the invention what is claimed as new is:

1. A baby spoon comprising, in combination, a spoon having a handle bent into the form of a closed loop, a cover portion adapted to be secured to the spoon, means on the cover for engaging the edge of the spoon to hold the cover in place thereon and a loop member attached to the cover and linked with said handle.

2. A baby spoon comprising, in combination, a spoon having a handle bent into the form of a closed loop, a cover portion adapted to be secured to the spoon, means on the cover for engaging the edge of the spoon to hold the cover in place thereon, a loop member attached to the cover and linked with said handle and interengaging means on the handle and loop member for holding the cover in operative position.

In testimony whereof I affix my signature.

ROBERT E. HODGMAN.
